UNITED STATES PATENT OFFICE.

HARRY W. MITCHELL AND PETER LA GRASSA, OF NEW YORK, N. Y., ASSIGNORS TO
NIGHT AERO ADVERTISING CORPORATION, OF NEW YORK, N. Y., A CORPORATION.

ADVERTISING SIGN.

Application filed July 3, 1923. Serial No. 649,346.

To all whom it may concern:

Be it known that we, HARRY W. MITCHELL and PETER LA GRASSA, citizens of the United States, residing at New York, in the county 5 of New York and State of New York, have invented certain new and useful Improvements in Advertising Signs; and we do declare the following to be a full, clear, and exact description of the invention, 10 such as will enable others skilled in the art to which it appertains to make and use the same.

Our invention relates to improvements in advertising signs and the present disclosure 15 is directed more particularly to an illuminated sign for the purpose of displaying advertising matter at night, through the instrumentality of an aircraft which carries the sign.

20 The principal object of the invention is to provide a simple and light, yet a very conspicuous sign which is carried by an aircraft in downwardly spaced relation therewith, the sign being disposed horizontally 25 in spaced relation with the machine, to avoid as much resistance as possible and to prevent the sign from interfering in any manner with proper functioning of the machine. This is particularly advantageous when the 30 sign is carried by a supporting plane of the craft, which is in most instances preferred.

Another object of the invention is to provide novel supporting means for a plurality of letters which may be attached to the supporting means at any of a number of points 35 along its length, thus permitting the letters to be properly arranged for displaying any desired advertisements.

A still further object is to provide a sign 40 structure which may be supported from the two main spars of a supporting plane of the machine, and may be readily detached when desired.

With the foregoing in view, the invention 45 resides in the novel subject matter herein-after described and claimed, the description being supplemented by the accompanying drawings.

Figure 1 is a sectional view through a supporting plane of an aircraft and our invention attached to the main spars of the plane.

Figure 2 is a fragmentary bottom plan view.

Figure 3 is a horizontal sectional view on 55 line 3—3 of Fig. 1.

Figure 4 is a detail vertical sectional view on line 4—4 of Fig. 2.

Figure 5 is a vertical sectional view as indicated by line 5—5 of Fig. 4.

Figure 6 is a sectional disassembled perspective view showing more particularly the manner of connecting the letters detachably with the supports therefor.

The drawings above briefly described, 60 illustrate the preferred form of our invention, for purposes of illustration, and in these drawings we have illustrated a conventional type of supporting plane 1 for an airplane, seaplane or other aircraft. The numerals 2 (see Fig. 1) designate the main 65 spars of the plane 1 and we prefer to support the sign which we have devised, from these spars. To this end, we secure vertical hangers 3 detachably to the spars 2, by screws or other desired means 4 and the 70 lower ends of said hangers carry a pair of parallel letter-supporting bars 5 which are preferably of angular form in transverse section, in order that they may be very light 75 and at the same time sufficiently strong. We 80 have illustrated rivets 6 securing the hangers 3 to the vertical flanges of the bars 5, but bolts or other attaching means could of course be used if desired.

The horizontal flanges of the bars 5 are 85 provided with longitudinal slots 7 and it will be seen that each slot may extend substantially throughout the length of its respective bar, or that a plurality of shorter slots could be used in place of one long slot. 90 These slots are intended to receive bolts 8 by means of which any of a number of thin sheet metal letters 9, may be attached to the bars 5. These letters may be of any preferred construction, but in order that they 95 may be conspicuously seen at night, we prefer that they shall be provided with a plurality of electric bulbs 10 receiving their current from a storage battery carried by the aircraft, the battery being supplied with 100 current by means of an appropriate motor-driven generator.

In the construction shown, each letter 9 is of channel form with its side flanges 105 extending downwardly at opposite sides of the electric lights 10. The upper side of each letter is provided at suitable locations with slots 11 through which the bolts 8 pass, and in order to reinforce the slotted portion of each letter, the latter is prefer- 110

ably provided on its upper side with plates 12 having slots 13 registering with the slots 11.

By providing the construction disclosed or 5 a substantial equivalent thereof, a sign and supporting means therefor are provided, of such nature and location on the machine, that they will not interfere with flights and proper control of the machine. While the 10 letters 9 are of course visible during daylight, much more conspicuous advertising is produced by flying at night with the electric lights 10 disclosing the shapes of the letters, but not illuminating the carrying 15 plane to detract from the advertisement.

Particular attention is directed to positioning the sign in a horizontal plane in downwardly spaced relation with a supporting plane of an aircraft or in a similar relation with another part of the craft, as this 20 positioning will offer practically no resistance and will not interfere with proper engagement of the supporting plane or other part, with the air.

25 As excellent results may be obtained from the details disclosed, they may be followed if desired, but within the scope of the invention as claimed, numerous minor changes may be made.

30 We claim:

1. The combination with a motor-driven plane-supported air craft; of horizontal bars under a supporting plane of the craft

and extending longitudinally of said plane, 35 rigid hangers for said bars detachably secured to said plane and suspending said bars in a common substantially horizontal plane, a horizontal row of horizontal letters contacting with the lower sides of said bars and substantially co-extensive with said supporting plane, said letters being applicable to said bars at different points along the length of the latter, and means for detachably and rigidly securing said letters to said bars.

2. The combination with a motor-driven aircraft having a supporting plane provided with main longitudinal spars; of a horizontal row of horizontal letters under said plane, horizontal bars under said plane extending longitudinally thereof and detachably carrying said letters, and rigid connecting means between said bars and said main spars of the plane.

3. A sign adapted for carriage by an aircraft, comprising a plurality of bars having hangers for supporting them horizontally under a supporting plane of the aircraft, said bars having longitudinal slots, letters contacting with the lower sides of said bars, 50 and attaching bolts for said letters passing through the latter and said slots.

In testimony whereof we have hereunto affixed our signatures.

HARRY W. MITCHELL.
PETER LA GRASSA.
